UNITED STATES PATENT OFFICE

115,165

DESIGN FOR A COLOR CAMERA

Thomas S. Curtis, La Canada, Calif.

Application March 18, 1939, Serial No. 83,676

Term of patent 7 years

To all whom it may concern:

Be it known that I, Thomas S. Curtis, a citizen of the United States, residing at La Canada, in the county of Los Angeles and State of California, have invented a new, original, and ornamental Design for a Color Camera, of which the following is a specification, reference being had to the accompanying drawing forming a part thereof.

Fig. 1 is a perspective view of a color camera showing my new design;

Fig. 2 is a top plan view of the same;

Fig. 3 is a side elevation of the same.

I claim:

The ornamental design for a color camera, as shown.

THOMAS S. CURTIS.
